(57) **CLAIM**

The ornamental design for a converting machine, as shown and described.

DESCRIPTION

FIG. 1 illustrates a perspective view of an exemplary embodiment of a converting machine of the present invention; FIG. 2 is a front view of the converting machine of FIG. 1; FIG. 3 is a back view of the converting machine of FIG. 1; FIG. 4 is a right side view of the converting machine of FIG. 1; FIG. 5 is a left side view of the converting machine of FIG. 1; FIG. 6 is a top view of the converting machine of FIG. 1; and, FIG. 7 is a bottom view of the converting machine of FIG. 1. The broken lines in the drawings depict unclaimed environmental subject matter.
